CONTAINING UNIT

Frederick O. Johnson, Chicago, Ill., assignor to
 International Harvester Company, a corpora-
 tion of New Jersey

Application August 10, 1946, Serial No. 689,786

4 Claims. (Cl. 312—31.1)

1

This invention relates to an improved breathing means for controlling the humidity of a container. More specifically it relates to an improved breathing device for keeping a container and a long-term storage unit substantially dehumidified over long periods of time.

It is an object of this invention to provide an improved breathing means for a container adapted to contain objects that must be kept free of moisture.

It is another object to provide an improved breathing means for an outdoor storage unit, said breathing means being effective to keep the interior of said unit substantially free of moisture over long periods of time and through all types of atmospheric changes.

A further object is to provide an improved inexpensive storage unit that will keep articles free of moisture over long periods of time and that does not require extensive service and upkeep.

Another object is to provide a breathing means for an enclosure containing objects which must be kept dry, said breathing means including a chamber which has a volume at least equal to the maximum change in volume of the air within the enclosure due to atmospheric conditions.

Another object is to provide a breathing unit for an enclosure containing objects which must be kept dry, said breathing unit including a chamber which retains dry air that has expanded from the enclosure into said chamber, and from which the dry air may be drawn upon contraction of the air within the enclosure due to atmospheric changes.

Another object is to provide an improved breathing unit for a container, said breathing unit including a passage which is adapted to contain dry and moist air, and having means within said unit for minimizing turbulence of the air within said passage, thereby eliminating substantial mixing of the moist air with the dry air which will initially be drawn into the container upon contraction of the air therein due to atmospheric changes.

A still further object is to provide an improved breathing means for a container, said breathing means being effective to dehumidify the air as it enters the container, said means also including a chamber which will collect and substantially retain the dehumidified air from the general atmosphere as it leaves said container due to atmospheric changes.

Other objects will become more readily appar-

2

ent upon an examination of the following specification when read in conjunction with the drawings, in which:

Figure 1 is an elevational view in cross-section through a container showing an improved type of breathing means.

Figure 2 is a sectional view taken on the line 2—2 of Figure 1.

Figure 3 is a sectional view taken along the line 10 3—3 of Figure 1.

Figure 4 is a side elevational view of an outdoor type of storage unit having portions broken away to show relevant parts of the invention.

Referring particularly to Figures 1, 2, and 3, 15 a container is generally designated by the reference character 10. The container 10 includes a cylindrical body 11 which is closed at its lower end by means of a bottom portion 12, thereby forming a containing chamber 12'. The phantom lines indicated by the reference character 13 represent an object contained within the chamber 12'.

The upper portion of the cylindrical body 11 is closed by a combined cover and breathing unit 25 generally indicated by the reference character 14. The cover or breathing unit 14 consists of a pair of upper and lower annular plate members 15. The lower plate member 15 is integrally formed with a vertically extending cylindrical band which extends beyond the upper surface of the upper plate member 15 and is suitably connected to said plate in sealing engagement by means of brazing, welding or other conventional methods. A breathing chamber 17 is 30 formed between the upper and lower plate members 15. A vertically extending ribbon-like element 18 is spirally wound within the chamber 17 and forms a labyrinth passage 19 of relatively small cross-sectional area. As best shown 35 in Figure 2, the passage 19 is extremely long and tortuous, this feature being of prime importance as will presently appear. The upper and lower ends of the element 18 are connected to the upper and lower plates 15 in sealing engagement so 40 that air passing through this passage will have to follow all the convolutions of the spiral.

Centrally located and at one end of the passage 19 is a breathing tube or conduit 20 which extends vertically through and beyond the plate 50 member 15. The conduit 20 includes openings 21 in communication with the passage 19. The conduit 20 is in communication with the atmosphere by means of openings 22. A weather cap 23 is suitably fastened over the upper end of 55 the conduit 20.

As best shown in Figure 2 the maximum peripheral end of the passage 19 is provided with a plurality of peripherally extending slots 24. The slots 24 are immediately adjacent to a mass of desiccant material 25 which is compacted between the outer peripheral surface of the element 18 and the inner surface of the cylindrical band 16. A pair of annularly extending shelves 26 are provided for retaining the desiccant material 25 in a compacted form. As best shown in Figure 3 the lower plate member 15 is provided with a plurality of slots 21, said slots serving to place the chamber 12' and the chamber 17 in communication with one another.

As indicated in Figure 4 an outdoor storage unit is generally designated by the reference character 30. The storage unit 30 includes a horizontal concrete base 31 which is imbedded in the earth 32. A plurality of enclosures 33 are fastened in the concrete base 31 and these enclosures are constructed of wire mesh sprayed with concrete. They are then suitably finished with a water-proof coating, thus providing an inexpensive and readily assembled construction. Each enclosure 33 is provided with a containing chamber 34. The containers 10 previously described are suitably supported within the chamber 34 by means of transverse supports 35. Each enclosure is charged with sufficient desiccant to sufficiently dry the contained air and objects stored therein.

In order to keep the enclosures 33 dehumidified, a pair of breathing units 39 are provided. Each breathing unit 39 consists of a pair of casings 40 and 41 suitably connected for communication with one another by means of a conduit 42. The casing 40 is provided with a dehydrating chamber 43. A plurality of trays 44 are connected within the casing 40 in a staggered manner to form a circuitous path through which the incoming and outgoing air must follow. Each tray contains desiccant material indicated by 45.

The casing 41 includes a breathing chamber 46 provided with a plurality of horizontally extending baffles connected to the casing 41 in a staggered manner to provide a circuitous path for incoming and outgoing air. A breathing tube 49 is connected to the casing 41 to provide for communication of the chamber 46 with the atmosphere.

In operation the article 13 is placed within the containing chamber 12' and the container is closed by means of the combined cover and breathing unit. The article or object to be stored is generally provided with a desiccant bag (not shown) or is sprayed with a desiccant to effect initial drying of the air within the chamber 12'. But for the breathing conduit 22 the chamber 12' is thus hermetically sealed.

As the air within the container 10 contracts due to atmospheric changes, the air that is contained within the passage 19 is forced through the desiccant and into the chamber 12'. The air thus having passed through the desiccant is substantially dried or dehumidified. Thus the air surrounding the article to be stored is free of moisture and corrosion or damage to the article is avoided. The air which has entered the chamber 12' is, of course, immediately displaced with outside air which still contains substantial moisture.

As the dry air within the chamber 12' expands due to atmospheric change, the reverse cycle takes place. Some of the dry air leaves the chamber 12' and reenters the passage 19, thereby forcing some of the moisture laden air back into

the outside atmosphere. The passage 19 is constructed so that it has a predetermined volume which is of prime importance. It can readily be computed what the maximum change in the volume of air within the chamber 12' might be under varying atmospheric conditions. Therefore depending upon the contemplated use of the container, the maximum changes are anticipated and the combined cover and breathing unit 14 is provided with a passage which will have a volume at least equal to the maximum change in the volume of the air within the chamber 12'.

Therefore, despite a maximum expansion of the air within the chamber 12' due to atmospheric conditions, the dry air leaving said chamber will be retained in the passage 19. Thus when the cycle is again reversed it is the dry air which will reenter the chamber 12'. At no time will the dry air escape from the passage 19 in any sufficient quantity, nor will moist air reenter the container. Thus, of course, the desiccant will be usable over great lengths of time without replacement or service. Since, because of the volume of the passage 19, the dry air is retained in the passage, any moisture which might enter the desiccant after the initial cycle would have to enter by diffusion only.

During the stage of the cycle when dry air is within the passage 19, the long and labyrinth shape of the passage 19 is especially effective. The narrow cross-sectional area of the passage with respect to its length will decrease the rate at which moisture might be carried to the desiccant by diffusion.

Assuming a stage in the cycle wherein the passage 19 is only partially filled with dry air, that is, air which has previously passed through the desiccant, the remaining portion of the passage is then of course filled with air that has entered from the outside and has a high moisture content. It is now, of course, extremely desirable to prevent the dry air and the moist air from mixing at the point of separation. In order to prevent such mixing due to the turbulence caused by convection currents, the long passage of narrow cross-section is especially effective. The narrowness and extent of the passage minimizes any turbulence in the air and thus mixing of the dry with the moist air is substantially prevented.

Thus it can readily be seen that a container of this type can be used for long periods of time without replacing the desiccant and without extensive maintenance. The maximum volume of the air developed within the container is of course dependent upon the size of the article to be stored and the changes in the atmosphere. Since these conditions can generally be readily anticipated, the size of the combined cover and breathing unit can be predetermined.

The principles incorporated in the container can, of course, be incorporated in shipping containers or any other type of enclosure where it is desired to keep articles dry for long periods of time. It is readily adaptable to warehouses, building construction, etc.

The container 10 is especially adaptable to the outdoor type of storage unit indicated in Figure 4. The storage unit 30 is extremely simple to manufacture and requires very little upkeep. Since this type of construction can be placed in any outdoor area, articles may be kept dry over long periods of time in an inexpensive and efficient manner. The outdoor storage unit 30 and the breathing unit 39 are similar in principle to the breathing unit 14. As the pressure within

the enclosures 33 decreases, the incoming air passes through the circuitous passage 48 of the breathing chamber 46. The air thereupon passes over the desiccant in the dehydrating chamber 43. Upon the air within the enclosures 33 expanding, due to atmospheric changes, the reverse process takes place. The casings 41 are so constructed that the minimum volume of each casing 41 is equal to one-half the total maximum change of the volume of the air in the space surrounding the containers 10. In other words, the combined volume of both the casings 41 is at least equal to the maximum change in the air which might be developed within the enclosures due to atmospheric expansion. The chamber 46 is provided with the circuitous passage, similar to the spiral labyrinth 19 of the container. The effect of the circuitous passage 48 is similar to the passage 19 and the unit functions in a like manner since the same principles are utilized. It is an adaptation of the same principle to a different type of construction. The dry air is retained in the passage 48 and is redrawn into the enclosures upon changes in the atmosphere. Since each container 10 is provided with its own breathing units 14, which combinedly functions with the breathing units 39, double assurance is provided that the objects within the containers will not be exposed to moisture. It is, of course, adequate to store any conventional type of container or object within the enclosures 33, and the breathing units 39 are sufficient to control the moisture content.

It can be seen that the objects of the invention have been fully achieved, and it must be understood that modifications may be made which do not depart from the spirit of the invention as disclosed nor as defined in the appended claims.

What is claimed is:

1. In combination with a storage unit having a casing for containing an object, a breathing system for said casing including a chamber in communication with the atmosphere and with said casing, said chamber being formed with a continuous labyrinth passage of narrow cross-section relative to its length, the volume of said continuous passage being at least equal to the maximum change in the volume of air developed within said casing due to atmospheric changes, and a dehydrating means associated with said chamber and with said casing, said dehydrating means including a desiccant material between said casing and said passage.

2. In combination with a container, a combined cover and breathing unit for said container

comprising a pair of spaced elements connected to form a chamber, a spirally wound element positioned between said spaced elements to form a continuous labyrinth passage in communication with said container, the volume of said passage being at least equal to the maximum change in the volume of the air developed within said casing due to atmospheric changes, a desiccant material at one end of said passage, and a conduit at the other end of said passage, said conduit being in communication with said passage and the atmosphere.

3. In combination with a storage unit having a casing for containing objects to be stored, a breathing unit comprising a first chamber having a plurality of desiccant filled trays arranged to provide a circuitous air passage, a conduit in communication with said first chamber and said casing, and a second chamber in communication with said first chamber, said second chamber having a labyrinth passage in communication with the atmosphere, the volume of said first chamber being at least equal to the maximum change in the volume of air developed within the casing due to atmospheric changes.

4. In combination with a storage unit having a casing for containing objects to be stored, a breathing unit comprising a first chamber having a plurality of desiccant filled trays arranged to provide a circuitous air passage, a conduit in communication with said first chamber and said casing, a second chamber in communication with said first chamber, said second chamber having a labyrinth passage in communication with the atmosphere, the volume of said first chamber being at least equal to the maximum change in the volume of air developed within the casing due to atmospheric changes, and a desiccant element within said casing.

40 FREDERICK O. JOHNSON.
